Application June 18, 1951, Serial No. 15,579

Term of patent 7 years

(Cl. D61—1)

To all whom it may concern:

Be it known that I, Grace B. Schwartz, a citizen of the United States and resident of the city of Los Angeles, county of Los Angeles, State of California, have invented a new, original, and ornamental Design for a Film Viewer, of which the following is a specification, reference being had to the accompanying drawing forming a part hereof, in which:

Fig. 1 is a top plan view of a film viewer, showing my new design;

Fig. 2 is a side view;

Fig. 3 is a bottom plan view;

Fig. 4 is a front view; and

Fig. 5 is a rear view thereof.

The essential features of my design reside in a film viewer having a top and bottom of sub-

stantially the same appearance, with the sides and parts of the end showing a very prominent central ribbed band in combination with the frame-like appearance as seen in Fig. 5, all as illustrated on the drawing.

I claim:

The ornamental design for a film viewer, substantially as shown and described.
